UNITED STATES PATENT OFFICE.

WILLIAM H. GLENN, OF EL PASO, TEXAS.

MOP.

1,360,926.

Specification of Letters Patent. Patented Nov. 30, 1920.

Application filed June 26, 1920. Serial No. 392,119.

To all whom it may concern:

Be it known that I, WILLIAM H. GLENN, a citizen of the United States, residing at El Paso, in the county of El Paso and State of Texas, have invented certain new and useful Improvements in Mops, of which the following is a specification.

This invention relates to mop attachments for brooms.

10 An important object of the invention is to provide a device of the above mentioned character which may be readily attached to the broom and maintained in position thereon.

15 A further object of the invention is to provide a device of the above mentioned character which is simple in construction and includes novel means for preventing lateral shifting when in place on the broom.

20 Other objects and advantages will be apparent throughout the course of the following description.

In the drawings, wherein like numerals are employed to designate like parts throughout, Figure 1 is a perspective view of the device attached to a broom.

Fig. 2 is an enlarged perspective view of the device detached.

Fig. 3 is a vertical transverse sectional view through the lower portion of the attachment, and

Fig. 4 is a perspective view of one of the mop element attaching strips and securing strings.

35 In the drawings, wherein for the purpose of illustration is shown a preferred embodiment of my invention, the numeral 5 designates the body portion of a broom of ordinary construction, provided with the usual handle 6. My invention includes a body portion 7, preferably of heavy fabric, having a front portion 8 and rear portion 9. The front and rear portions 8 and 9 are tapered, decreasing in width upwardly to correspond generally with the shape of the broom. The front portion 8 is somewhat wider than the rear portion 9 and is provided near its upper end with an opening 10 adapted to receive the handle 6 of the broom. The opening 10 is preferably provided with a binding strip 11, stitched to the front portion 8. The rear portion 9 is substantially shorter than the front portion 8 and is provided at its upper ends with a pair of attaching

45 strings 12 stitched thereon. The strings or tapes 12 are preferably attached to the rear portion 9 in the manner shown in Fig. 2, diverging outwardly for a purpose to be described.

The lower end of the body portion is provided with a plurality of mop elements 13 extending upwardly a substantial distance from the bottom of the body portion on the outside of both the front and rear portions 8 and 9. The mop elements 13 consist preferably of strings arranged vertically of the body portion and attached thereto by means of parallel strips 14, stitched to the body portion 7 substantially centrally of the mop elements.

One of the mop element attaching strips 15 is provided with a comparatively short end 16 extending beyond the edge of the body portion. The opposite end of the attaching strip 15 is looped at 17 to pass around the edge of the broom and has an elongated end 18 adapted to extend across the opposite side of the broom. The end 18 of the attaching strip 15 is preferably passed beneath the strands of one of the 80 mop elements, as shown in Fig. 3.

In attaching the device to a broom, the opening 10 is slipped over the end of the broom handle and dropped down to contact the upper end of the body portion of the 85 broom, as shown in Fig. 1. The rear portion 9 is then passed around the lower end of the broom and up on the opposite side thereof, whereupon the strings 12 may be passed around the broom handle and tied, 90 as shown in Fig. 1. By attaching the strings 12 to the rear portion 9, as shown in Fig. 2, the strings 12 may be drawn tightly around the handle 6 without danger of loosening the stitching of the strings. The end 18 of the attaching strip 15 is then passed around the body portion of the broom and out on the opposite edge thereof, as shown in Fig. 2, and tied as indicated in Fig. 1. The string 15 serves to prevent shifting of the 95 lower end of the mop upon the broom.

It is to be understood that while I have described the preferred embodiment of my invention, various changes in the shape, size, and arrangement of parts may be resorted to without departing from the spirit of the invention or the scope of the subjoined claims.

Having thus described my invention, I claim:

1. A mop attachment for brooms comprising a body portion adapted to be folded

110

transversely substantially centrally thereof to form front and rear portions, said front portion being provided with an opening to receive the handle of the broom, and a pair 5 of attaching strips carried by said rear portion and adapted to be tied about the broom handle.

2. A mop attachment for brooms comprising a body portion including front and 10 rear portions, said front portion being provided with an opening adapted to receive the handle of the broom, means for attach-

ing said rear portion to the broom, a plurality of mop elements, and a plurality of attaching strips adapted to secure said mop elements to said body portion, one of said attaching strips being provided with extensions adapted to be tied about the broom. 15

In testimony whereof I affix my signature in presence of two witnesses.

WILLIAM H. GLENN.

Witnesses:

J. H. McBROOM,

NORMAN E. SNODGRASS.
